ABSTRACT

A stand for holding a musical accessory at a convenient level having a base comprised of a plurality of adjustable telescoping members forming a U-shape base support, which can be adjusted to extend around other equipment in a crowded stage area, thereby conserving space and enabling the stand to be conveniently situated closely together with such other equipment, and in addition being used as an instrument and equipment support stand that can be compacted into a convenient small package for purposes of storage and transport. A structure for folding for carrying and transportation is particularly disclosed.

ADJUSTABLE MUSICIAN'S STAND**CROSS REFERENCE TO RELATED APPLICATION**

This application is a Continuation-in-Part application based upon and taking priority from U.S. patent application Ser. No. 11/183,558, filed on Jul. 18, 2005 and assigned U.S. Pat. No. 7,176,366 which was based upon and took priority from U.S. patent application Ser. No. 10/823,092, filed on Apr. 13, 2004, now U.S. Pat. No. 7,131,615 which was based upon and took priority from U.S. patent application Ser. No. 10/145,051 filed on May 14, 2002, now U.S. Pat. No. 6,720,490.

BACKGROUND OF THE INVENTION**1. Field of the Invention**

The present invention relates to equipment stands used by musicians, and more particularly to stands for microphones, music, instruments and amplifiers, and more particularly still to a stand having a horizontally adjustable base particularly for use on a crowded stage or performing area and capable of extending around floor supported musical equipment as well as supporting various musical instruments and musical accessories that folds into a compact and easily carried and transported configuration. More particularly still, the present invention provides for folding of such base for carrying and transportation plus special folding arrangements for the base to facilitate transportation.

2. Preliminary Discussion

Individual musicians such as guitarists or vocalists, as well as musical groups or bands, often perform in venues such as clubs, bars and the like where the stage or performing area is quite small. For example, many corner bars or clubs do not even have a separate stage area, and performers must clear an area of tables, chairs and other like items prior to setting up their equipment. In such situations, there is barely room for a band having several members to set up such equipment, which typically includes several microphone stands, amplification equipment, control processors, a keyboard, drum set and the like. In addition, after such equipment has been set up, there may be little room left over for the band members to move around during their performance, as they typically may desire. Even in clubs having larger performing areas, space is still at a premium, since most band members prefer to be able to move around the stage freely without having to worry about tripping over or running into their equipment.

Performers who both play an instrument, such as an electric guitar, while also providing vocals' encounter a slightly different space problem. Particularly where there is a limited area to move around, such performers will often remain in a more or less stationary position. However, it can be difficult to orient both a foot controller or processor equipment for an electric guitar and a microphone or music stand so that both are in sufficiently close proximity to the performer so that they can be reached without the performer having to continually change or shift positions. This difficulty is largely due to the shapes of such equipment. A typical microphone stand is comprised of a vertically adjustable telescoping pole connected to a round, weighted base situated directly beneath the pole, and is normally placed more or less directly in front of the performer so that the microphone is in close proximity to the performer's face and mouth whenever vocals are required. Electronic guitar foot controls or processing equipment are usually enclosed in a generally rectangular holder or box-like structure which also must be placed in close proximity to the

performer so that such foot controls can be comfortably reached by the performer without requiring him or her to shift positions or move away from the microphone. However, placement of the round microphone stand base directly in front of the performer leaves little room for the foot controller. This conflict can adversely affect the quality of the performance, since the microphone and foot controls often may be required to be used simultaneously. The instant invention attempts to overcome this conflict by providing a microphone stand having a base that can be horizontally adjusted for placement around a foot controller or other objects, permitting both the microphone and foot controls to be directly in front of, and therefore within easy reach of, the performer.

In addition, there is frequently other equipment to support as well as floor equipment which is conveniently bracketed by any equipment stands necessary to support elevated equipment and the present music accessories stand is particularly designed to support such equipment while conserving floor space.

3. Description of Related Art

Numerous examples of arrangements for stacking and folding microphone or music stands, or for adjusting the height of such stands, are known in the prior art. In addition, other types of music equipment such as electronic keyboards are usually provided with a support or frame structure. However, the inventor is not aware of a stand for holding a microphone, sheet music, or a small instrument such as a harmonica or large equipment or instruments which stand can be horizontally adjusted to be situated around other equipment used by a musician, such as a foot controller or audio amplifier, thereby making it easier to simultaneously use such equipment while also conserving space in a small or cramped stage area. Nor is the present inventor aware of any previous wide bases for musical equipment and microphone stands such as that of the inventor which can be folded up for transportation in a manner similar.

Despite the numerous microphone and music stands known in the prior art, each of which provides its own degree of utility, there is a need for a stand having a base portion which incorporates usable space in the center and which can be adjusted to conserve space on a cramped or crowded stage or performing area so as not to interfere with the placement of other music or performing equipment and which conveniently folds for transportation.

OBJECTS OF THE INVENTION

It is therefore a primary object of the invention to provide a stand for holding a microphone, sheet music, instrument or the like that can be folded into a compact arrangement for transport and storage.

It is a further object of the invention to provide a stand providing floor space in the center portion of the base of the stand to accommodate music or other performing equipment.

It is a further object of the invention to provide a stand having a base portion comprised of a plurality of telescoping members which are independently adjustable.

It is a still further object of the invention to provide a stand wherein the telescoping members can be adjusted so as to surround or avoid other music equipment or control boxes on a stage floor such as speakers, foot controllers or effects processors.

It is a still further object of the invention to provide a base for a microphone, instrument, or music stand which can be easily and quickly set up and stored in a compact configuration when not in use.

Still other objects and advantages of the invention will become clear upon review of the following detailed description in conjunction with the appended drawings.

SUMMARY OF THE INVENTION

A stand for use as a microphone stand, music stand, or instrument stand is provided having a telescopingly adjustable base arrangement which is designed to be used particularly in relatively cramped stage or performing areas where there is a need to conserve space, although such arrangement could be used in any performing area. Performers, particularly those musicians or bands performing in a small club or bar environment, often encounter a problem in that there is insufficient room to set up all of their electronic equipment in a reasonably effective manner. The present invention addresses this problem by providing a stand having a generally U-shaped frame or support providing floor space within the center of the "U" and wherein the length of the support members is adjustable so that the support members can be positioned compactly around other equipment such as processors or controllers, thereby more efficiently using the available floor space in setting up such equipment. The pitch or angle of the vertical microphone support column can be adjusted using screw-type foot members on the bottom of the stand. In addition, the foot members provide sufficient room between the floor and horizontal support members so that electric control wires powering the effects processor, instruments, or other equipment can be slipped under such members. The stand as well as the instrument and equipment support features also may be simply and quickly folded or compacted into an easy to carry package for transportation and storage purposes.

BRIEF DESCRIPTION OF THE DRAWINGS

FIG. 1 is side elevation of the stand of the present invention.

FIG. 2 is a top or plan view of the base portion of the stand of the present invention.

FIG. 3 is a top or plan view of the base portion of the stand similar to FIG. 2 with the individual telescoping base members extended to or toward their maximum.

FIG. 4 is a rear view of a slightly alternative version of the base, as it would originally be viewed from the audience side.

FIG. 5 is a rear view of the base as shown in FIGS. 1-3, as it would normally be viewed from the audience side.

FIG. 6 is an isometric view of the base surrounding a typical foot control device.

FIG. 7 is an isometric view of an artist using a microphone mounted on the stand of the invention shown in FIG. 5.

FIG. 8 is an isometric view of an artist using the stand of the invention shown in FIG. 4 as a music stand.

FIG. 9 is a side elevation of another slightly alternative embodiment of the invention.

FIG. 10 is a side elevation view of another alternative embodiment of the invention.

FIG. 11 is a rear view of the stand shown in FIG. 10, as it would normally be viewed from the audience side.

FIG. 12 is a front view of the stand shown in FIGS. 10 and 11 with the leg members slightly pivoted away from a support surface.

FIG. 13 is a top view of the base of the stand shown in FIG. 10.

FIG. 14 is a close-up isometric view of the arrangement for attachment of the leg members to the support member in FIG. 10 shown disconnected or disassembled for clarity.

FIG. 15 illustrates a slightly alternative arrangement for attachment of the leg members to the microphone support member also shown disconnected or disassembled for clarity.

FIG. 16 illustrates a further embodiment of the invention incorporating a wider U-shaped stand in which a wider and more sophisticated foot controller may be accommodated directly in front of a musician on a stage or the like and accommodating a square microphone support post.

FIG. 17 shows the microphone stand shown in FIG. 16 10 disassembled and laid out on a surface ready to be assembled for use either in the configuration shown in FIG. 16 or with an alternative arrangement or configuration as a backup stand as shown in FIG. 18 in which a loudspeaker may be accommodated in the central section and several forms of racks may be mounted on the support post.

FIG. 18 shows the alternative configuration into which the equipment of FIG. 17 may be formed together with a loudspeaker that fits between the telescoping leg portions and a guitar supported on the rack.

FIG. 19 is a side view of the stand configuration shown in FIG. 18.

FIG. 20 is an elevation of a modification of the arrangement shown in FIG. 19 with the addition of two additional side posts for the support within easy grasp of additional items such as two additional guitars as shown.

FIG. 21 is a view of the parts of the apparatus shown in FIG. 20 laid out ready to be assembled including side brackets to support the telescoping side posts.

FIG. 22 is a plain view of an improved end construction for the base of the stand in which the extensible sides of the U-section may fold parallel to the main or front piece.

FIG. 22A is an enlarged view of the locking action of the catch which holds the pivoting end pieces in the folded position.

FIG. 23 is a side elevation of a portion of the base of the invention showing an alternative arrangement in which a microphone stand may be attached to the side of the base and extended to the underlying surface to serve as an additional brace to prevent forward instability of the stand.

FIG. 24 is a plain view of the base of the invention shown in FIG. 23 without the center post or microphone post.

FIG. 25 is a side view of a typical screw threaded interconnection on adjustable length sections.

FIG. 26 is a side view of a typical twist type friction lock between sliding post parts which is used on most telescoping microphone stands and can be adopted for use in the present invention when the interconnecting slide members are cylindrical in shape.

FIG. 27 is an isometric view of a double screw threaded interlock sliding holder for use on the vertical supports or posts of the invention where additional security in the interlock with the vertical support is desirable or required.

FIG. 28 is a side view of an alternative bracket for support of the side posts shown in FIG. 20.

FIG. 29 is a side view of the bracket of FIG. 28 installed on an end leg of the stand base.

FIG. 30 is a top view of another preferred embodiment of the stand base of the present invention.

FIG. 31 is a side view of the embodiment of the stand base of the present invention shown in FIG. 30.

FIG. 32 is an elevation front view of the stand base shown in FIGS. 30 and 31 in a compact or storage position.

FIG. 33 is a view of another preferred embodiment of the stand of the present invention further having an amplifier support with supplemental support leg members.

FIG. 34 is a view of the embodiment of the stand of the present invention shown in FIG. 33 supporting a guitar and a large amplifier.

FIG. 35 a view of the parts of the apparatus shown in FIGS. 33-34 laid out ready to be assembled including the modified support tray and supplemental tray support members.

FIG. 36 is another view of the apparatus shown in FIGS. 33-35 being used to support a small amplifier and a guitar.

FIG. 37 illustrates the apparatus shown in FIGS. 33-36 compacted into the stand base and rod section and instrument and equipment support sections.

FIG. 38 illustrates the apparatus as shown in FIG. 37 with the stand base and rod section and instrument and equipment support sections being a single package.

FIG. 39 is a broken away isometric view of one embodiment of the new folding base of the invention.

FIG. 40 is a top view of the folding base shown in FIG. 39.

FIG. 41 is a front elevation of the base of FIG. 40.

FIG. 42 is a side elevation of the base of FIGS. 40 and 41.

FIG. 43 is a rear elevation of the base of FIGS. 40 through 42 showing in dashed outline how the base folds upwardly around or on either side of a microphone support rod.

FIG. 44 shows the base of FIGS. 39 through 43 in folded configuration.

FIG. 45 is an isometric broken away view of an alternative center section of the folding base of the invention.

FIG. 46 is a side view of a preferred adjustment and locking arrangement of the extensible center and side legs of the present invention.

FIG. 47 is a cross section of the inner telescoping leg shown in FIG. 46.

FIG. 48 is an isometric view of another adjustment and locking arrangement of the extensible center and side legs of the present invention.

FIG. 49 is an isometric partially disassembled view of an alternative embodiment of the folding base of the invention.

FIG. 50 is an isometric partially broken away construction detail of the central section of a reversed center fitting showing a preferred arrangement for mounting a microphone stand.

FIG. 51 is a side cross section of the center section shown in FIG. 50.

FIG. 52 is an isometric view of a preferred downwardly folding stand base of the present invention.

FIG. 53 is an isometric view of the folding base of the invention shown in FIG. 52 with the center section adjusted upwardly to provide more clearance below in accordance with the invention.

FIG. 54 is a front view of an embodiment of folding base of the invention which folds downwardly.

DESCRIPTION OF THE PREFERRED EMBODIMENTS

The following detailed description is of the best mode or modes of the invention presently contemplated. Such description is not intended to be understood in a limiting sense, but to be an example of the invention presented solely for illustration thereof, and by reference to which in connection with the following description and the accompanying drawings one skilled in the art may be advised of the advantages and construction of the invention.

It is frequently necessary or desirable to situate control pedals and other control equipment for loud speakers and other musical, performance and special effects equipment directly in front of a performer, which performer usually is also using a microphone or the like in his or her musical or

other artistic performance. In a very large music hall or similar performing environment, there are usually sound men and other technical personnel to handle the operation of sound equipment, modify its effects from time to time as necessary, and generally monitor and adjust the rendition of any performance. A lone performer before smaller audiences, on the other hand, must modify the sound and musical effects him or herself and, since such performer cannot or should not, from an artistic viewpoint, be seen continually adjusting various knobs, dials, switches and the like, foot control pedals are usually provided to allow the performer adequate control of the technical aspects of sound control. Operation of such foot controls is not as visible and distracting to an audience as hand manipulation would be, and frequently an artist's hands are otherwise occupied in any event. The most convenient and logical location for such foot control and other equipment is directly in front of the performer. However, where the performer is using a standup microphone, as is frequently necessary, if the artist's hands are busy, the microphone base must also be in front of the performer unless the microphone can be supported on a pivoted or counterbalanced beam or pole arrangement from the side, which is sometimes done, or can be hung from the ceiling of the performing area, which is seldom possible in smaller or more general, as distinguished from, professional or specialized performing facilities. Consequently, there is considerable agonizing, adjusting and improvising by an artist before each performance trying to arrange the floor equipment such as foot controls and the like and the base of microphones and the like with respect to the performer. Not only is this improvising period time-consuming, but it also is tension-inducing for the performers and distracting during actual performance. The present inventor, having been presented as a performer with the problem, has ingeniously solved it by providing not only a microphone stand providing floor space in the center directly under the microphone, but one that is freely adjustable so that such stand can be readily adapted to performing equipment of various dimensions while maintaining the floor space taken up by the various equipment at a minimum. Thereby, a very significant problem for performers has been solved in a simple and expedient manner.

The same problem which occurs with microphone bases also frequently occurs with respect to music stands, instrument stands where an instrument must be partially supported or where a single musician must take up alternative instruments during a performance, and in such cases the present invention provides an open base stand with adjustable lateral dimensions which may be used also with great effectiveness. The stand of the invention or base for a stand of the invention is particularly useful also where the stage or performing area is cramped and lacking in space as very many less professional performing areas are.

The inventor has now also discovered that his basic microphone base which provides room at the center of the base for foot controls and the like, as shown and described in his previous application with respect to which this application is a continuation-in-part, can also with little or no substantial modification be used to support holders for instruments behind or to the sides of the performer and can in the same manner surround a loudspeaker or amplifier equipment behind the performer. The inventor has designed further attachments for his stand and base including an improved arrangement for decreasing the dimensions of the folded base for storage and transportation between appearances of the artist.

As shown in FIG. 1 hereinafter, the present applicant's basic microphone base can be conveniently carried in a fairly

compact package together with a telescoping microphone support inserted through the front of the base and clamps within and when the stand is to be used with instrument racks or supports or a stand rather than a microphone stand these can be added to the package as shown in FIGS. 37 and 38. The dependent side legs of the stand are in these embodiments, however, somewhat cumbersome and the entire assembly arranged for carrying by the carrying strap has some resemblance at first glance to a rapid fire machine firearm sometimes referred to as an "Uzzi" which some musicians might prefer, but others may not prefer. The present inventor, therefore, has now developed an improved folding base in several embodiments which is more compact and easier to transport in a compact package with or without the microphone stand rod or vertical support member. Some further developments are shown in FIGS. 39 through 54 and include certain additional refinements of the basic arrangements of the base structure.

Reference will now be made in detail to a presently preferred embodiment of the invention as illustrated in the accompanying drawings. Whenever possible, the same reference numbers will be used throughout the drawings to refer to the same or like parts.

FIGS. 1-9 illustrate a first preferred embodiment of the invention, with FIGS. 4 and 8 illustrating a slightly alternative embodiment, while FIGS. 10-15 illustrate another possible alternative embodiment. FIGS. 16-29 illustrated another alternative embodiment, while FIGS. 30-3x illustrate yet another alternative embodiment. FIG. 1 is a side elevation view of the first preferred embodiment of the adjustable musician's stand 10 of the present invention. While such example of the invention illustrates the stand 10 supporting a microphone 40, it is envisioned as well as illustrated in the alternative embodiments below that the stand 10 can also be used as a music stand, instrument or equipment support stand, or the like. In addition, the scale of FIG. 1 may appear distorted because the microphone 40 appears large compared to the microphone support rod or member 30. However, support rod 30 should be understood to be considerably longer, it having been foreshortened in the figure by not showing a central section indicated by dotted lines, and in actuality, the usual microphone support rod will be three or four times as lengthy and usually telescopically adjustable as described below. A typical microphone supported on a stand in accordance with the invention in use by a performing artist is shown in FIG. 7.

Referring still to FIG. 1, stand 10 is generally comprised of a base 20 supporting or being coupled to a vertically extending post or support member 30, with microphone 40 secured on the upper end of support member 30 by bracket or clip 42. Microphone cable clips, not shown, may also be situated on support member 30 to secure a microphone cable, also not shown. A swiveling boom may also be provided as is known in the prior art. Preferably, the height of support member 30 is telescopingly adjustable, and is comprised of an outer telescoping member or portion 31 which is secured at its lower end in base 20, and an inner telescoping member or portion 32. The relative position of such members can be fixed at a desired height or position by a threaded locking mechanism 34 such as a threaded wing nut fastening of a type known in the prior art located on the upper end of outer member 31, whereby relative movement between the telescoping members during use is prevented and the length of the vertical support member 30 is temporarily fixed or maintained as desired. Alternatively, as illustrated generally in FIGS. 7 and 8, inner telescoping member 32 can lock in position by rotat-

ing inner member 32 in relation to outer telescoping member 31, or various other clamping means known to those skilled in the art can be used.

FIGS. 2-5 illustrate in various views and with various orientations the supporting base 20, while FIG. 6 illustrates the base 20 surrounding a typical foot controller device designated by reference number 90. As will be shown below, the supporting base 20 of the inventor's stand 10 is constructed with a U-shaped frame so that the center portion is relatively open, thereby leaving room for other equipment to also be placed directly in front of the performer. In addition, the legs of supporting base or base central extensions 22 are also horizontally adjustable, so that the base of the stand can be more easily and efficiently arranged around other equipment on a crowded stage. In addition, each of the base support members can be detached from the stand 10 or otherwise adjusted for easier storing or carrying.

Still referring to FIGS. 2-5, base 20 is comprised generally of hub or central portion 22, first and second telescoping or extensible corner members 50a and 50b, and first and second telescoping or extensible leg members 60a and 60b. In combination, such parts form a generally U-shaped frame or supporting base having an open center and enable base 20 to be situated in a finite number of different generally horizontal configurations so that the stand 10 does not interfere with the placement of other electronic equipment on a stage or performing area directly in front of the performer. Each of such parts is preferably made from the same material, which can be any suitable material such as anodized aluminum, hard plastic, steel or the like.

Upwardly facing stand socket 24 is situated generally at the midpoint of central portion 22. As is most clearly shown in FIGS. 1 and 4, outer portion 31 of telescoping microphone support 30 is placed in and coupled to socket 24 by threaded securing members 70 and 72. While stand socket 24 is shown in the FIGS. as having a rectangular shape to accommodate the rectangular base of coupling member 36 on the bottom of the outer portion 31 of microphone support rod 30, such socket 24 can be in any shape depending primarily upon the shape of particular coupling member. In addition, coupling member 36 may be either a permanent part of the support rod 30 or may be slip fitted over the bottom of the support rod 30. Socket 24 is preferably coated with a rubber material that acts as a barrier to prevent floor vibrations from passing through the stand and support rod to the microphone, thereby greatly reducing the risk of feedback vibrations interfering with the quality of the sound.

First and second outer sleeves 26 and 28 of central portion 22 extend horizontally from opposite sides of sleeve or stand socket 24, while corner members 50a and 50b are telescopic coupled in sleeves 26 and 28. As best shown in FIG. 3, corner member 50a is comprised of first inner sleeve 54a, corner piece 56a, and, aligned perpendicular to first inner sleeve 54a, outer sleeve 58a. Similarly, corner member 50b includes second inner sleeve 54b, corner piece 56b, and, aligned perpendicular to second inner sleeve 54b, outer sleeve 58b. See FIG. 3, which shows the inner sleeves extended and therefore visible. First and second inner sleeves 54a and 54b are sized to telescopically couple within first and second outer sleeves 26 and 28 on central portion 22, respectively. Threaded screw members 74a and 74b are adjustably secured in threaded apertures generally near the outer ends of sleeves 26 and 28, respectively, for jam holding inner sleeve sections 54a and 54b in position with respect to outer sleeves 26 and 28. Although parts 54a, 56a and 58a, and 54b, 56b and 58b, respectively, are labeled separately, preferably they are integrally made as a single cast or otherwise fabricated piece. In

addition, in each case, the threaded screw members are shown as having a wing nut on the exterior of an underneath threaded fastening to jam against a sliding section below to maintain the sections in position with respect to each other. However, the wing section could also be a hexagonal or other head fastener or bolt adapted to impinge against the adjacent member and jam fit the two together. Other suitable fasteners could also be used. Hand screw members 76a and 76b are threadably secured in apertures on the top face of corners members 50a and 50b, respectively, while screw members 78a and 78b are threadably secured in apertures near the outer ends of sleeves 58a and 58b, respectively, to maintain the inner sleeves 54a and 54b in the end pieces 50a and 50b. Ground engaging or foot members 51a and 51b, shown in FIGS. 4 and 5, are located on the bottom side of corner pieces 56a and 56b to actually support the front of the base 20 on an underlying support surface. Such foot members may be fixed on the bottoms of corner members 50a and 50b or may preferably be adjustable with respect to the corner members. Suitable adjustment may be obtained by thread attachment into the corner members or alternatively by the use of threaded type jam fittings, not shown, in the end of the corner pieces.

First and second leg members 60a and 60b are comprised of inner telescoping members 62a and 62b having connected on their outer ends members 64a and 64b. Telescoping members 62a and 62b are sized to extensibly or telescopingly couple with outer sleeves 58a and 58b, respectively. In addition, as shown in FIG. 6, adjustable screw-type foot members 66a and 66b are preferably threadably secured to the bottom side of end members 64a and 64b so that the pitch or angle of the vertical microphone support column can be adjusted. In most cases, support member 30 is preferably angled towards a musician playing an instrument so that the stand does not interfere with the playing of such instrument held in front of the musician. A further angle or pitch to the support column can be provided by increasing the height or depth of corner members 56a and 56b, as shown in FIG. 4, or by adding as shown an additional piece onto the bottom side of corner members 56a and 56b, as illustrated in FIG. 8. Such arrangement also provides room for heavier cables to pass underneath the support members of base 20.

In FIG. 6, base 20, see FIGS. 1 and 2, is shown placed on a generally horizontal surface such as a stage or performing area and adjusted so that the telescoping members are surrounding a foot controller 90 of a type typically used in controlling an electric instrument such as an electric guitar. Base 20 is configured so that it surrounds the controller 90 on three sides, with central portion 22, see FIG. 2, extending along the entire front of the controller 90, first corner member 50a being situated at the left front corner of the controller, first inner and outer leg members 58a and 60a extending along one side of the controller, second corner member 50b being positioned at the right front corner of the controller, and second inner and outer leg members 58b and 60b extending along the opposite side of the controller. After the base 20 is situated as desired, screw members 74a-b and 78a-b are tightened so that the telescoping members are secured in such position. In addition, as indicated above, stand 10 can be easily angled slightly forward or to one side by adjusting the position of foot members 51a-b and 66a-b, respectively. The foot members could also be used to compensate for an unevenness or slant in the stage floor or performing area, which might occur particularly in an older performing facility. In addition, as shown in FIGS. 7 and 8, foot members 51a and 51b and 66a and 66b raise the base 20 off the stage floor a sufficient distance so that electric wires 92 operating the effects controller 90, music equipment, or other wires can be easily

slipped between floor and the adjustable base members. As indicated above, the angle of the support member can also affect the ability of a musician to play his or her instrument, and can be adjusted accordingly using the foot members.

5 By using the telescoping base 20 of the present invention, vertical member 30, partially shown as outer telescoping portion 31 in FIG. 6, supporting microphone can be situated so that it is in close proximity to the foot controller and both are in close proximity to the musician while performing with 10 the foot controller 90 centrally located. The musician therefore no longer has to strain or lean to one side, or otherwise compensate for the disparate positions of the microphone and foot controller. In addition, such arrangement more efficiently allocates or utilizes the available space, which is 15 important particularly in a small or cramped performing area. Such an arrangement would not be possible using prior art base systems, which typically comprise a generally circular weighted base member, because it would be impossible to centrally position such base member so that it does not interfere with the placement of the controller.

20 FIG. 7 is an isometric view of the stand 10 of the invention in use on a stage by a performer 100 playing an electric guitar. Vertical member 30, see FIG. 1, holds or supports a microphone 40, while base 20 surrounds a controller 90, which the 25 performer is using to modulate or otherwise control the details of his performance. It is evident how the stand enables the performer to have both the microphone and the control stand conveniently before him. In addition, the stand is tilted forward so that there is room for the performer to play the 30 guitar while also having the microphone close to his mouth.

FIG. 8 is an isometric view of the stand 10 of the invention with the base 20 as shown in FIG. 4 used to support a music stand 110, rather than a microphone, of a musician playing an electric guitar. It is evident how the stand of the invention 35 facilitates positioning of the music directly in front of the musician with the controls for the instrument also readily available to the musician's feet.

Other variations to the base 20 may also be provided. For 40 example, it is envisioned that a rubber or other vibration damping layer on base 20 may be provided in addition to rubber coated stand socket 24 to reduce any vibrations from the equipment from interfering with the microphone. FIG. 9 is a side elevation view of another possible alternative embodiment of the invention wherein an extra stabilizing member 98 is provided extending generally opposite the direction of members 58a and 58b from the front side of stand socket 24. Stabilizing member 98 is provided to eliminate the possibility that the base 20 might tip in such direction, although by angling the base generally forward using the foot members, such possibility has already been substantially lessened. There is always a possibility of the stand being accidentally impacted by movements of the performer or by other accidental forward impact, however, and the stabilizer member 98 guards against such possibility. Member 98 is 45 preferably vertically pivotable so that after stand 20 has been situated as desired, member 98 is pivoted downwardly until it contacts the stage surface, similar to a pivoting door stop. Suitable pivoting may be attained in several different manners, including an adjustable hinge arrangement or the like, not shown. Stand socket 24 in FIG. 9 has been slightly modified to accommodate placement of member 98. Alternatively, rather than having a single centrally located support member 98, a pair of such support members could be located on sleeves 26 and 28 or first and second corner members 50a and 50b.

50 FIGS. 10-15 illustrate another alternative embodiment of the stand 110 having a slightly different base arrangement but

11

wherein the base is also telescopingly adjustable so that it can be accommodated to or placed or situated around other equipment in a crowded stage area. In general, in such alternative embodiment of the base, instead of the base being formed from heavy tubular or cast sections of whatever composition, such base is formed from lighter plastic or aluminum sections, which sections may be square or rectangular or tubular in cross section. The heavy tubular or cast construction tends to be fairly steady upon a performing stage or platform because of its substantialness, but heavier and more difficult to transport. The alternative base is formed from lighter, thinner tubular sections that can be easily folded together and transported, but may be less steady and more easily toppled by accidental impact without being unduly unstable. The same principle of having the supporting arm extending upwardly at an angle from the base and having legs or base sections extended to the side and then rearwardly at the ends in the same direction as the inclination of the microphone or other support and having a space in the center into which foot control equipment may be centered is adhered to and the base sections are adjustable in two directions, i.e. forward and back and to the side by preferably a telescoping construction. Since the tubular sections are fairly light gauge, the device, while still fairly steady, is lighter and easy to transport. The central section may also be easily disassembled, if desired, for transportation.

FIG. 10 is a side view of stand 110 which is comprised of base 120, adjustable vertically extending support member 130, and any suitable clip or holder for microphone 140. As shown in FIGS. 11 and 12, base 120 includes two outwardly extending leg members 132 and 134. Preferably, each leg member 132 and 134 is comprised of inner and outer telescoping sections 132a-b and 134a-b, which are secured or held together by threaded jam members 138. In addition, leg members 132 and 134 preferably have downwardly curved outer ends which form feet 140. Leg members 132 and 134 are generally pivotable from a position shown in FIG. 11, where the legs are situated so that they are generally horizontal to the floor or stage surface while support member 130 is perpendicular to such leg members, to a position such as shown in FIG. 12, where the legs have been pivoted so that they are angled in relation to the floor, as indicated by the arrows. As is visible in FIG. 13, which is a top view of the base 120, feet 140 are generally angled downwardly and then extend at right angles from leg members 132 and 134 so that a U-shaped arrangement is formed. Extending outwardly from the ends of feet 140 are telescoping side or foot members 142, which are adjustable in the same manner as in the previously described embodiments.

FIGS. 14 and 15 show two slightly different arrangements for securing leg members 132 and 134 to microphone support member 130. In FIG. 14, apertures 154a, 154b, and 154c are positioned on or near the ends of support member 130 and leg members 132 and 134, respectively. Bolt 150 may be passed through each of such apertures and secured by nut 156 so that leg members are pivotable about the same point. In FIG. 15, leg members 132 and 134 have upper and lower generally horizontal offset portions 158 and 160 to which apertured end 154a of support member 130 is pivotably secured. Either arrangement is an acceptable means for enabling the angle of leg members 132 and 134 to be easily adjusted. It will be understood that the intersecting sections containing fastening orifices will be oriented so that when connected together by suitable fastenings the base sections will extend to the side while the microphone or apparatus support section will extend upwardly with a slant in the same direction as the end of the legs of the base. As shown in FIG. 10, for example,

12

support member 130 is preferably angled slightly forwardly as in the previous embodiments. In addition, FIG. 11 shows that sufficient room is provided between the floor or stage area and leg members 132 and 134 for wiring or cables to be strung, making setup of electronic equipment even easier. Each of the embodiments shown accomplishes the same purpose of providing sufficient space directly in front of a performer for placement of equipment in addition to a microphone stand, thereby improving the ability of a musician to give an effective and enjoyable performance.

The inventor has now as the result of further development work realized that the invention has applicability to other uses by a musical artist than use merely as a microphone or music stand the base of which, by surrounding a foot control apparatus can provide better use of stage space. Stage space is of tremendous importance where such space is not particularly great. It has now become evident that the same principle according to which the microphone stand base has been constructed can be applied as well to effective use of the stand of the invention as a stand for holding instruments such as spare, or alternative, guitars or other stringed instruments, or, indeed, any instrument at all, plus, where desired smaller electronic control apparatus or other elements are used support of such equipment and further that the U-shaped base will fit very neatly about relatively large heavy equipment such as, for example, amplifier equipment which can fit nicely into the broadly U-shaped space within the open side of the adjustable and foldable base. For example, a musical artist may wish to use the stand as a microphone stand with the base compactly surrounding a foot control of various types, plus use another more or less identical stand having its base surrounding a loudspeaker plus use various trays or holders attached to a sturdy upstanding rod or a post extending upwardly from the base, whereby electronic control elements of the foot controller may be supported upon a rack clamped to the supporting rod or post. A loudspeaker may be placed in the space defined by the legs of the base, with the further support at a quick accessibility level upon the post of a spare instrument such as a guitar resting upon brackets clamped at a convenient height upon the support rod. The inventor has also designed special strengthened brackets for use on his support rods or posts connected to his base plus a smaller folded base attained by use of folding telescoping end pieces rather than fixed telescoping end pieces of earlier embodiments thereby adding increased convenience for transportation and/or storage. The inventor has also created a combined microphone stand and front balance leg for his adjustable musician's stand. Such further improvements and adaptations are shown in the following described drawing figures.

FIG. 16 is an isometric view of an expanded foot pedal type control for controlling the sound and sound effects of a loudspeaker and sound effects system surrounded by a longitudinally and laterally expandable base in accordance with the inventors principal embodiment shown in FIGS. 1 through 9 the embodiment of the microphone stand 10a shown in FIG. 16, however, being significantly wider appropriate to the wider foot control. The foot control 90a has a series of foot pedals or buttons 91 which can be pressed to implement various electronic and sound modulation effects as known in the art, plus a longer rocking pedal 92 which will usually control the loudness of the system dependent upon how far the pedal is depressed as also well known in the art. The pedal 92 is designed to have a fair range of movement so that precise control of volume can be effected. The base 20 has fairly long tubular sections 22a extending from the central holder or socket 24a or across the central portion of the base 20 under the microphone socket 24a. A pair of two legged L-shaped

end pieces 50a and 50b as in FIG. 2 complete the end of the base 20 and telescoping legs 62a and 62b extend from these. A microphone stand or post 30a extends upwardly from the socket 24a. FIG. 16, therefore, illustrates a stand basically similar to the stand shown in FIGS. 1 through 9 extended about a wider foot control than shown in FIGS. 6 to 8. Such foot control may have its state of the art electronics either in the foot control itself or housed in a second controller which can be supported away from the floor upon a stand or table or the like where it is better separated from shocks and damage due to rough treatment of the foot controller by the instrumentalist or performer.

FIG. 17 shows in isometric projection from the front above the parts of the stand 10a laid out upon a surface after disassembly with the base 20 still extended, for illustration, about the foot control 90a. In addition, several innovations are shown which are not shown in FIG. 16 including a sturdy square tubular microphone stand 30b which accommodates a telescoping central square tubular member 30c for expandability with a cylindrical microphone support fitting 30d attached to the top with a microphone 40 at the end. Such square tubular support 30b, as will be explained, may do double duty as part of a support stand when used alternatively to support other elements of a musician's equipment including electronic control means plus extra instruments and the like. Also shown in FIG. 17 are two instrument brackets 93 and 94 which can be fitted over the square tubular member 30b and clamped with screw clamps plus a tray support 95 also provided with a square tubular clamp which fits over the support rod 30b and can be clamped by wing type threaded clamping means at any desired level. The small adjustable screw-type feet 51a and 51b can be seen on the front (as used for support of a microphone) can be seen in FIG. 17 on the base 20 at the bottoms of the two end pieces 50a and 50b. The further brackets 93 and 94 plus the tray support 95 may be used attached or clamped to the support rod 30b when used as a utility or spare instrument support. See FIGS. 18 and 19.

FIG. 18 is a front elevation and FIG. 19 is a side elevation of the base and support of the invention when used in an alternative fashion, for example, in FIGS. 18 and 19, as a support for a spare instrument readily and almost instantaneously available to an instrumentalist from a rack in back of such instrumentalist. Racks or brackets 93 and 94 clamped onto the support rod 30b are shown as well as tray-type support 95 also clamped on the support rod 30b. The tray-type support 95 is shown with the electronic control case 96 for the foot control unit 90a supported upon it. It will be understood, however, that the tray 95 could be used to support anything else desired including even the lower end of one of the instruments. Ordinarily, however, the bracket 93 will be used to support the lower end of an instrument and the bracket 94 will be used to hold the upper end of the instrument. It may be readily noted in FIG. 19 that each of the brackets 93, 94 and tray 95 are provided with two threaded interlocks on their slide bases encompassing the support rod 30b. Also the socket 24, as in FIGS. 4 and 5, is provided with dual screw clamping means. Under the tray bracket 95 supporting the electronic control 96 and between the legs 58a and 58b is a large amplifier 97 through which the musician's program and musical accompaniment may be broadcast. The slide portion of the brackets 93 and 94 and tray 95 may have larger or smaller open slide portions depending on which portion of the support post is to be clamped upon.

FIG. 20 is an elevation of a further elaboration of the stand apparatus shown in FIG. 18 in which not only is there a broad U-shaped base 22 surrounding an amplifier 97 with an electronic controller 96 accommodated on a tray 95 above it

clamped to a square or rectangular post to which brackets 93 and 94 are also attached or adjustably clamped, but there are in addition two further support posts 150 secured to the outer legs 58a and 58b preferably in a manner to be described. 5 These two posts 150 are mounted in sockets 151 extending upwardly from the legs 58a and 58b and as shown have double threaded clamp means 152 to clamp the posts 150 securely in them in a manner similar to that shown in FIGS. 1, 4, 5 and 19. These sockets 151 may be attached to the legs 58a 10 and 58b in several manners the easiest way being shown in FIG. 21 described below.

FIG. 21 shows the various pieces of the stand shown in FIG. 20 laid out after or before assembly except for the end pieces or corner pieces 50a and 50b. There are shown two 15 alternative central pieces or front legs 26a and 28a and 26b and 28b each with a central socket 24 for receipt of the central post 30b or 30c. To these would be added a corner piece 50a and 50b, not shown, arranged with square tubing to receive the ends of the base legs 26 and 28 plus the end sections or 20 legs 62a and 62b. The section 152 and 153 may be substituted for these end legs. Sections 152 and 153 both have an upstanding socket 154 and 155 which may accommodate posts 150 together with their brackets 93 and 94 for support of musical instruments such as guitars and the like, 156 and 157. 25 (See FIG. 20). A further arrangement for attaching the posts 150 is shown in FIGS. 29 and 30.

FIG. 22 discloses a further improvement of the end legs 58a and 58b shown in previous figures. In this improved arrangement the end section instead of being a rigid fitting 30 50a and 50b shown in previous figures with sleeves for telescopic connection to other sleeve or leg sections such end piece or leg sections, is formed from a section of square tubing 58c and 58d hinged to the sliding tubing of the sections 54a and 54b at hinges 59a and 59b. The telescoping ends 62a 35 and 62b shown in previous figures continue to extend from the sections 58c and 58d. A spring catch or lock 120 engages with a detent 121 when the sections 58c and 58d are swung out perpendicular to the sections 54a and 54b when in use. The hinged sections may be swung back, however, into storage 40 position as indicated by dashed line 123 at which time they lie compactly parallel to the sections 54a and 54b as shown in FIG. 22 on the right of the drawing creating a more compact package for storage. FIG. 22A is an enlarged view of the spring catch 120 and the detent on the end of telescoping sections 54a and 54b.

The present inventor has also realized that the lower portion of center or support post 30 of the stand of the invention may be substituted for the forward leg 90 shown in FIG. 9 for balance. This is accomplished as shown in FIGS. 23 and 24 50 where it is shown that the socket 24a can be attached to the base 20 on the side of the front cross members 26 and 28 and be provided with an open bottom so that the post 30 itself can be extended downwardly to contact the stage as a further balancing leg as well as a support post. In this arrangement the socket 24a can be provided with a single or double screw 55 clamping arrangement, particularly, since considerable of its weight will be supported by the performing stage surface itself.

The telescoping members of the stand of the invention can 60 in each case be interlocked in operating position either by a screw-threaded clamping arrangement particularly as shown as a generality in FIG. 25 for either rectangular or cylindrical members or by a common twist friction lock when used on cylindrical members. Such twist friction locks are very common, for example, on microphone stands. See FIGS. 25 and 65 26 where FIG. 25 indicates diagrammatically the use of a screw-type interlock to lock two sliding or telescoping mem-

bers together and FIG. 26 illustrates diagrammatically an equivalent twist friction lock for the same purpose, but usually confined to use on a cylindrical member. The arrows indicate the sliding relationship between the members when unlocked as well as the twisting movement of the lock section.

FIG. 27 is an isometric view of one of the applicant's sliding brackets with double screw interlock means. If the post upon which it was to be mounted was cylindrical the collar or sleeve would be preferably cylindrical as well, but the double screw threaded interlock would remain basically the same.

FIG. 29 shows a connector 158 having a lower tubular section which may slide over one of the end legs 58a or 58b and interlock therewith by means of threaded members 159 and 160. The end post 150 may then be inserted into the socket 24a. A screw-threaded foot 161 may be screwed into the bottom of the fitting or connector 158. FIG. 29 shows the fitting 158 connected to or between the legs 50a and 60a and/or 50b and 60b.

The inventors modification of the basic stand of the invention so it can by the use of various additional accessories plus the use of improved refinements such as folding end legs on the base, arrangement of the upper socket on the front side of the base so it can serve double duty as a balancing leg and use of double screw locked brackets to hold accessory trays and brackets to the supporting brackets has substantially increased the utility of the invention.

In addition to the improvements and modifications described above, through trial and error the present inventor has now also made several further improvements to the present invention that increase its overall functionality, particularly when used for holding heavy equipment such as an amplifier, and providing a more compact arrangement for storage and carrying of the stand.

FIGS. 30 and 31 are top and side views of another preferred embodiment of the adjustable stand base 10c of the invention. Such embodiment is similar to the embodiments shown in FIGS. 1-9 above, except in the present embodiment the adjustable foot members 51a and 51b in FIGS. 4 and 5, rather than being attached to the bottom sides of corner pieces 56a and 56b of corner members 50a and 50b, are attached in housings on the front side of such corner pieces. More particularly, in FIGS. 30 and 31, threaded housings 306 and 307 are shown permanently secured such as by welding to the front side walls of corner pieces 56a and 56b, respectively. Housings 306 and 307 may be in the form of long threaded nut members into which foot members 51a and 51b are threadably movable to facilitate adjustment of the height or angle of stand. Similarly, foot members 66a and 66b, shown in FIG. 6 attached to the underside of end members 64a and 64b of telescoping members 60a and 60b, have been moved to the rear side surface of such members 64a and 64b, where threaded housings 308 and 309, which may also be long threaded nut members, are secured preferably by welding.

Several advantages result from positioning foot members 51a and 51b in housings on the front side of corner pieces 56a and 56b, and positioning foot members 66a and 66b in housings on the rear surface of members 64a and 64b. First, such arrangement gives the stand additional support or stability by widening its base, which makes the stand much less likely to tip in either a forward or rearward direction if it is bumped during a performance, which occurs rather frequently. In addition, as shown in the FIGS. below, such arrangement also facilitates folding or storing of the stand in a substantially more compact configuration for transport to and from a performance or storage when it is not in use. To allow for such

compact storage arrangement, another modification must be made from the previously described embodiments in that the sides or ends 310 and 311 of corner pieces 56a and 56b of corner members 50a and 50b are cut away or removed, creating opening 312 in such members. With that the ends 310 and 311 of corner pieces 56a and 56b now being open, and since the inner ends of telescoping members 54a and 54b of tubular corner members 50a and 50b are also open, a through-aperture is created in which telescoping microphone support 30 may be slipped and secured for storage.

The method of storing stand 10c compactly will now be described with particular reference to FIG. 32. First, as shown by the dotted line 315 in FIG. 31, when it is desired to store stand 10c, the telescoping ends 54a and 54b (see FIG. 3) of corner members 50a and 50b are removed from first and second outer sleeves 26 and 28 of central portion 22, respectively, rotated ninety degrees in a counterclockwise direction, and then reinserted into such outer sleeves. Such arrangement is preferred because as a result, as shown in FIG. 32, the upwardly protruding stand socket 24 and outwardly extending sleeves 58a and 58b of corner members 50a and 50b are now in the same plane, which results in a substantially more compact storage arrangement. Next, telescoping microphone support member 30 having inner and outer telescoping sections is moved to an unextended position secured, and then is pushed in aperture 312 in one of the sides or ends 310 or 311 of corner pieces 56a and 56b until its end extends out the other side or end 310 or 311, as shown in FIG. 32. Once inserted, threaded jam-type screw members 74a and 74b may be tightened to secure corner members 50a and 50b and microphone support member 30 in such position. To facilitate transport or carrying of the stand 10c, an adjustable carrying or shoulder strap 320 is provided. Strap 320 includes a flexible strap section 321, and a pair of metal clip sections 322 and 323 on the ends of said strap section 321. Each metal clip section 322 and 323 has a threaded screw 324 and 325 connected thereto which can be inserted and secured in the top ends of threaded housings 306 and 307, respectively. Thus, as is evident from FIG. 34, the stand 10c is now in a complete storage configuration and may be easily carried to and from a performance by shoulder strap 320. It should be evident that stand 10c when stored in such manner takes up much less room and is significantly easier to carry and store than typical prior art microphone stands, while setup is still quick and easy.

FIGS. 33-41 illustrate another preferred embodiment of the invention that is most similar to the arrangement shown in FIGS. 17-19 above, but with further modifications made to the tray support 95, and in addition arranged so that it is also capable of being broken down into a compact storage configuration similar to stand 10c shown with reference to FIGS. 30-32. In particular, effects tray 95 has been modified so that it includes a pair of legs which enable such tray to be used to support large, heavy equipment such as an amplifier or speaker without fear of the stand collapsing or tipping over. As will also be shown, use of the tray to support an amplifier or speaker also enables such speaker or amplifier to be positioned at an upward angle so that the sound is directed upwardly rather than directly towards the musician.

Referring now to FIG. 33, illustrated there is an isometric view of the modified instrument and equipment stand 10d in an upright configuration ready for use, including the longitudinally and laterally expandable base in accordance with embodiment 10c shown in FIGS. 30-32. More particularly, the base 20 has fairly long tubular sections 26 and 28 extending from the central portion of the base 20 under the microphone socket 24, and with L-shaped end or corner members 50a and 50b completing the end of the base 20 and telescopic

ing legs 62a and 62b extending from these. As in embodiment 10c, to accommodate compact storage of the device as well as to improve the stability of the device, an aperture 312 is provided in the sides or ends 310 and 311 of corner pieces 56a and 56b, and foot members 51a and 51b are attached in threaded housings 306 and 307 on corner pieces 56a and 56b.

Microphone stand or post 30b of a sturdy square tubular type such as shown in FIG. 17 extends upwardly from the socket 24a, such stand accommodating a telescoping central square tubular member for expansibility. Attached to stand 30b are two instrument brackets 93 and 94 which are fitted over the square tubular member 30b and clamped with screw clamps. In addition, tray support 95a, also provided with a square tubular clamp which fits over the support rod 30b, is clamped to the support rod by wing type threaded clamping means at a desired level. Similar to the arrangement shown in FIGS. 18 and 19, as shown in FIG. 34, brackets 93 and 94 are used to support an instrument such as an electric or acoustic guitar G when such instrument is not in use. In addition, rather than placing amplifier A on the ground as in FIG. 18, such amplifier is placed on tray support 95a. Note that such amplifier A could be placed on tray support 95a so that it is upright or facing directly forwardly, or as shown in FIG. 34, it may leaned so that the front is pointed upwardly.

FIG. 35 shows in isometric projection from the front above the parts of the stand 10d laid out upon a surface after disassembly. Included is base 20 having center section 22 comprised of tubular sections 26 and 28 which meet at a central point below socket 24, L-shaped corner members 50a and 50b, telescoping or extensible leg members 60a and 60b, foot members 51a-b and 66a-b, and screw clamps 74a-b and 78a-b. Also shown separated are support rod sections 31 and 32, as well as instrument supports 93 and 94, and tray support 95a. Tray support 95a is different from tray support 95 shown in FIG. 17 in that it includes tubular side members 350 and 351 for attachment of L-shaped support members 354 and 356, respectively. Each L-shaped support member 354 and 356 is comprised of an inner telescoping member 358, a leg member 360 situated substantially a right angle from telescoping member 358, and a stop 362 welded to the outer end of telescoping member 358. As explained below, stops 362 act as a front lip on tray support 95a to prevent items placed on the tray support from slipping off. Also provided are screw pins 364 for locking members 358 at a particular telescoping position. The addition of support members 354 and 356 substantially increase the versatility of tray support 95a so that it can be used to support larger items such as large amplifiers and speakers without fear of the stand 10c tipping or such equipment falling off the front of the tray support. Finally, also shown in FIG. 35 as in the embodiment shown in FIGS. 30-32 is carrying or shoulder strap 320 including a flexible strap section 321 and a pair of metal clip sections 322 and 323 on the ends of said strap section 321 each having an aperture sized so that a screw 324 and 325 can be inserted in such aperture and threadably secured in the upper end of threaded housings 306 and 307, respectively on corner members 50a and 50b, respectively.

FIG. 36 illustrates one mode of use of tray support 95a, wherein it is used to support a relatively small sized amplifier A completely off the ground as well as a guitar G. Note in FIG. 36 that L-shaped support members 354 and 356 are each shown in a storage position, as they are not required to be used due to the small size of amplifier A. In FIG. 34, however, another mode of use of stand 10d, and in particular tray support 95a, is illustrated, wherein the tray support is used to support a large sized amplifier or speaker, as well as a guitar. In FIG. 34, tray support 95a is moved down lower on rod

section 31, such that leg members 360 of L-shape support member 354 and 356 are in contact with the stage or floor surface. To move tray support 95a into such position, the threaded pins securing tray 95a to rod section 31 are loosened and the tray support is moved to the appropriate height, wherein such pins are again tightened. Pins 364 holding L-shaped support members 354 and 356 to tray 95a, assuming they are originally positioned in a storage position as shown in FIG. 36 with the leg members 360 facing inwardly towards one another, are loosened and then telescoping legs 358 are completely removed from tubular side members 350 and 351, respectively. L-support member 354 is then rotated ninety degrees in a clockwise direction so that leg member 360 is touching the stage or floor, and then telescoping member 358 is reinserted into tubular side member 351 and tightened. Similarly, after L-support member 356 is completely removed from tray support 95a, it is rotated ninety degrees in a counterclockwise direction so that its leg member 360 is also in contact with the floor surface, after which telescoping member 358 is reinserted into side member 352 and tightened. Then, as shown in FIG. 34, large amplifier or speaker A as well as guitar G can be easily supported on stand 10d with little fear of tipping or collapsing, as the additional support member 354 and 356 will stabilize the entire stand by supporting much of the weight of the amplifier or speaker A and in addition giving the stand a wider base.

While stand 10d including instrument supports 93 and 94 and tray support 95a having additional leg members 354 and 356 result in a particularly sturdy and useful instrument and equipment support apparatus, as with the microphone stand shown in FIGS. 30-32, the inventor has also found that the stand 10d including such supports can also be broken down and arranged in a relatively small sized and easy to carry and store package. FIG. 35 illustrates all of the various parts of the stand 10d in a broken down configuration, while FIG. 37 illustrates the stand 10d compacted into two small packages, and FIG. 38 illustrates stand 10d compacted into a single package.

The method of storing the base 20 and support rod 30 portions of stand 10d are essentially the same as described above with reference to stand 10c shown in FIGS. 30-32. First, the telescoping ends 54a and 54b of corner members 50a and 50b are rotated ninety degrees in a counterclockwise direction with respect to the first and second outer sleeves 26 and 28 of central portion 22, and then are reinserted into such outer sleeves, and threaded jam-type screw members 74a and 74b are tightened to secure corner members 50a and 50b in such position. As a result, the upwardly protruding stand socket 24 and outwardly extending sleeves 58a and 58b of corner members 50a and 50b are now in the same plane and therefore take up less overall storage space. Inner and outer telescoping microphone support member sections 31 and 32 are then unextended and slipped through one of the sides or ends 310 or 311 of corner pieces 56a and 56b so that the opposite end protrudes out the other side or end 310 or 311. As a result, the entire microphone stand 10c may be easily broken down and stored in such compact configuration. Then, carrying or shoulder strap 320 (shown in FIG. 38) including flexible strap section 321 metal clip sections 322 and 323 on the ends of said strap section 321 is attached through apertures in each clip section 322 and 323 to threaded housings 306 and 307 by screws 324 and 325, respectively.

Next, instrument supports 93 and 94 and tray support 95a are secured together in a neat package, with the same screw clips that are used to secure the instrument supports to support 31 now being used to secure the supports to tray support 95a, also shown in FIGS. 37 and 38. Support 93 is secured so that

it is basically flush against the underside of tray support 95a, while support 94 is secured so that it is flush with the top surface of tray support 95a, with the screw clips being secured in notches in crosspieces that comprise part of the framework or structure of tray support 95a. Telescoping portions 358 of L-shaped tray support members 354 and 356 are secured in tubular side members 351 with leg members 360 facing inwardly toward one another rather than downwardly, and pins 364 are again tightened. As indicated above, instrument support bracket 94 is then laid on top of tray support 95a as shown in FIG. 37, with the pins of double screw interlock means used to secure connector 158 at a vertical position on support rod 30 now being used to secure the connector 158 to tray 95a with such pins situated in cutout sections in cross bar 370 of the tray support 95a. The pins are then tightened to secure bracket 93 in place. Similarly, instrument bracket 94, which has a single pin in connector 158, is laid flat on the opposite side of tray support 95a and then such pin is tightened in a cutout section of cross bar 378.

Once the combined stand base and rod sections 380 and instrument and equipment support sections 382 of the device have been arranged as just described, as shown in FIG. 38, such sections may then be secured together so that the stand 10d with the equipment holding supports is secured in a single compact package. To accomplish this, the combined instrument and support section 382 is first rotated one hundred eighty degrees from its orientation in FIG. 37, and is laid on top of stand base and rod sections 380. Prior to this, however, pins 70 and 72 on socket 24 are removed, so that the combined section 382 can lie flat on combined section 380. Tray support 95a includes a central bar 384 having apertures 385 and 386 (see FIG. 37), which are spaced apart so that they can be aligned with the apertures in socket 24. This is done, and then pins 70 and 72 are reinserted through apertures 385 and 386 in bar 384 and then into socket 24 and tightened. This will secure the sections 380 and 382 tightly together so that they can be carried and stored as a single package.

In addition to the previously presented embodiments, the present inventor has now conceived of several further improvements to his adjustable microphone stand. In one embodiment, the stand legs, in addition to being telescopingly adjustable, are foldable into a compact storage arrangement. In such arrangement, the side legs of the base are pivotally secured to center legs so as to be pivotable between a use position in which the side legs are perpendicular to the center leg, and a folded position in which the side legs are adjacent to and in parallel with the center leg. In addition, the telescoping center leg is formed in two sections which are pivotally connected to a central stand support member, and which sections are foldable into substantially vertical position. The stand base is easy to move between a use position and a folded or storage position wherein the center and side legs are all aligned in the same plane so that the device is less bulky to carry and store. The center legs are shown folding both upwardly and downwardly in different embodiments. In addition, various arrangements for securing the legs in an extended position, and for increasing the clearance under the center leg for wires and the like are provided. The present embodiments have a further advantage in that clearance under the center leg of the device for wires and the like is automatically provided.

Referring now to FIGS. 39-44, stand 410 is generally C-shaped as in the previously described embodiments, compare FIG. 40 with FIGS. 2 and 3 above, and includes a center leg section 412 and side leg sections 414 and 416. The legs of the center and side sections 412, 414, and 416 are telescopingly adjustable in a horizontal plane to allow the dimensions

of the base to be modified and positioned around stage equipment and the like so that the equipment is directly in front of a musician and to save space on a small, cramped stage area. In the previously described embodiments, however, the center section 412 of the stand was comprised of a single piece rigid member (such as reference numeral 22 in FIG. 1) having a centrally located upwardly facing stand socket and sleeves extending outwardly in opposite directions from the socket in which outer sleeves a pair of inner sleeves were telescopingly secured. In the present embodiment, on the other hand, the center section of the stand is comprised of a central member 422 having a centrally located upwardly facing stand socket 424 and a pair of U-shaped socket members or modified devises 426 and 428 situated on either side of stand socket 424. See FIG. 39. As shown in the exploded view in FIG. 39, first and second hollow center leg members 430 and 432 are pivotally secured in sockets 426 and 428 of central member 422, respectively so as to extend outwardly from opposite sides of central member 422. Hinge pins 434 of a known type are used to pivotally secure center leg members 430 and 432 in sockets 426 and 428, and are inserted through holes 436 provided on the inner ends 440 of leg members 430 and 432, and matching holes 438 in the front and rear vertical surfaces of sockets 426 and 428. The inner ends 440 of leg members 430 and 432 are also preferably rounded to facilitate the pivoting movement of such members. Telescoping center leg members 442 and 444 are sized to be slidably received in center leg members 430 and 432, respectively, where they are secured in a fully extended position, a fully retracted position, or at any desired position between a fully extended and a fully retracted position by screw-type knob clamps 446 which extend through threaded apertures 448 in center leg members 430 and 432 near the outer ends of such members and press against telescoping members 442 and 444 to hold them in place by friction.

Pivots secured to the underside of the telescoping center leg members 442 and 444 near their outer edges are side leg members 450 and 452. Hinge pins 454 of a known type are used to secure such leg members together, with a spacer such as a washer 456 (shown in FIGS. 41 and 43) being placed between the outer surfaces of legs to ensure that there is sufficient clearance for side leg members 450 and 452 to pivot into a storage position underneath center leg members 430 and 432, respectively, as will be described in detail below. Other arrangements for providing such clearance as will be evident to those skilled in the art may also be utilized. Inner telescoping side leg members 458 and 460 are sized to be slidably received in the open ends of outer side leg members 450 and 452, respectively, and may also be secured in a fully extended position, a fully retracted position, or at any desired position between a fully extended and a fully retracted position, by threaded clamps 462 which extend through threaded apertures 464 near the ends of outer side leg members 450 and 452, and press against inner telescoping side leg members 458 and 460 to hold them in place by friction. Screw clamps 462 are preferably situated on the outer side surfaces of the center leg members 430 and 432, as well as side leg members 450 and 452, so as not to interfere with any wires or equipment placed between such legs. Clamps 446 and 462 also preferably are provided with rubber tips to increase their frictional grip on telescoping leg members 442-444 and 458-460. Adjustable foot members 466 may be provided on the underside of outer and inner side leg members 450 and 458, respectively, or, as shown in FIG. 42, rubber end caps 468 may be provided on the ends of such leg members.

As indicated by the arrows in FIG. 40, side legs 414, and more particularly side leg members 450 and 452, are rotatable

inwardly so that they can be folded and positioned under center legs 430 and 432, respectively. In addition, as indicated above, center legs 430 and 432 are rotatably connected to centrally located socket member 422, and, as shown in FIGS. 43 and 44, are pivotable between a horizontal use position and a vertical storage position. Thus, with microphone stand rod or vertical support member 470 secured in stand socket 424 in central member 422 as in FIG. 44, and with side legs 450 and 452 folded and thus aligned with center legs 430 and 432, which are then folded upwardly, all of the legs of stand base 410 are aligned closely together in a vertical plane, forming a small and compact transport and storage package. As is most clearly illustrated in FIG. 39, spring clamps or pins 472 of a known type are mounted by welding or other suitable arrangement adjacent apertures on central member 422 so as to extend inwardly into and engage either holes 474 or 476 on the inner end of central leg members 430 and 432. When spring clamps or pins 472 are engaged in holes 474, leg members 430 and 432 are secured in a horizontal or use position, but when engaged in holes 476, leg members 430 and 432 are secured in a vertical or storage position.

FIG. 45 illustrates another alternative embodiment of the present invention, wherein instead of central support legs 430 and 432 folding upwardly relative to central stand support 422 as in FIGS. 39-44, central stand support 480 has essentially been turned so that legs 430 and 432 pivot or fold downwardly. One advantage of such arrangement is that spring clamps or pins 472 are not required to hold legs 430 and 432 in a vertical use position, as in such position the outer top surface of legs 430 and 432 will press against top surface 482 of member 480 and be prevented from rotating further in an upward direction. Further embodiments of this basic arrangement are described with reference to FIGS. 49-54 below.

FIGS. 46 and 47 illustrate an alternative arrangement for securing any of the pairs of telescoping legs of the stand base in a desired position. As shown in FIG. 46, inner telescoping member 490 is slidable in outer member 492 through the open end of such member. A hole 494 is provided near the innermost end of inner telescoping member 490, and a nut 496 is integrally formed or secured preferably by welding to the inner surface of member 490 adjacent hole 494. Meanwhile, a longitudinal channel is provided in the side surface of outer member 492, which channel is aligned with hole 494 in inner telescoping member 490, enabling a threaded bolt or knob similar to the threaded fastener 446 shown in FIG. 39 and preferably including a suitable washer member to be inserted into hole 494 and then engaged with the threads of nut 496, causing inner telescoping member 490 is pulled against outer member 492, while the washer and bolt press against the outer surface of outer member 492, holding it in place. Thus, in use the inner telescoping leg member 490 is simply moved to the desired length or position, after which bolt 498 is turned until such leg member is held tightly. As an alternative to attaching a nut to the inner surface of hole 494 in telescoping member 490, threads could be provided directly on the metal or other material adjacent hole 494 as it is bent inwardly, providing a less durable but equally efficient arrangement.

FIG. 48 illustrates another alternative arrangement for securing the inner telescoping leg members of the stand base at a desired length or position similar to that shown in FIGS. 46-47, but instead of placing a threaded aperture in the inner telescoping member, a threaded bolt 502 is secured extending outwardly from inner telescoping member 490 through longitudinal channel 497 in outer leg member 492. An internally threaded knob 504 may then be secured on bolt 502, so that as the knob is turned, inner telescoping leg member 490 is pulled

into contact with the inner surface of outer leg member 492, while knob 503 is pressed and frictionally held against the outer surface of leg member 492 adjacent channel 497. Once inner telescoping member 490 is placed in outer member 492 with bolt 502 aligned in channel 497, an end cap 501 is permanently secured over the outer end of outer member 492 to prevent the inner leg from being completely removed from inside the outer leg, which aids one in being able to more quickly adjust the legs and in packing and unpacking the structure in a considerably more organized manner. In the embodiment shown in FIGS. 46-47, this same organizational advantage is maintained as long as the screw knob is kept at least partially threaded in opening 492 on nut 496. FIG. 49 illustrates another embodiment of the invention 504 wherein the side legs of the device are not adjustable, i.e., there is no sliding or telescoping extension within or otherwise associated with them. While not as adaptable as the telescoping adjustable version of the invention, such arrangement is satisfactory where the depth of equipment placed between the legs is not too wide and the fold down arrangement of the legs of the stand can still be used.

FIGS. 50-54 illustrate a further downwardly folding alternative embodiment of the stand base of the present invention, wherein furthermore the amount of clearance for wires and the like available under the center leg is adjustable. Referring first to FIG. 52, stand 510 has the same C-shaped configuration as the previously described embodiments, and is comprised generally of a center leg section 512, and side leg sections 514 and 516. The legs of the center and side sections 512, 514, and 516 are telescopingly adjustable so that the dimensions of the base can be modified to fit around stage equipment and the like on a small, cramped stage area, also just as in the previous embodiments. As best shown in FIG. 50, similar to the embodiment shown in FIG. 45, center section 512 of the stand is comprised of a central member 522 having a centrally located upwardly facing microphone rod or support member receiving socket 524 and a pair of downwardly facing U-shaped socket members or modified devices 526 and 528 on opposite sides of stand socket 424. As shown in FIGS. 52 and 53, first and second center leg members 530 and 532 are pivotally connected in sockets 526 and 528, respectively, by hinge pins 534 which are inserted through aligned holes in sockets 526 and 528 and the inner ends of leg members 530-532. Inner telescoping center leg members 542 and 544 are sized to be slidably received in openings in the outer ends of center leg members 532 and 534, respectively, and may be secured in a fully extended position, a fully retracted position, or at any desired position between a fully extended and a fully retracted position. In the presently described embodiment, the adjustment arrangement shown in detail in FIGS. 46-47 is being used to secure center leg members 542 and 544 in a partially extended position by tightening of knobs 546, which knobs are attached to a threaded member that engages matching threads in an aperture in leg members 542 and 544, frictionally securing them against the inner surfaces of leg members 530 and 532.

Side leg members 550 and 552 are pivotally secured near their outer edges to the underside of center telescoping leg members 542 and 544, respectively, by hinge pins 554, with a spacer such as a washer being placed between the abutting outer surfaces of such legs to ensure that there is sufficient clearance for side leg members 550 and 552 to rotate underneath center leg members 530 and 532, respectively, in order to be placed in a storage position. Inner telescoping side leg members 558 and 560 are sized to be slidably received in open ends of side leg members 550 and 552, respectively, and may be secured at any desired position between a fully extended

and a fully retracted position. Although no securing arrangements are shown on the side leg members, it will be understood that any of the arrangements shown in the previous embodiments may be satisfactorily used. Adjustable foot members 566 may be provided on the underside of outer and inner side leg members 550 and 558, respectively, or alternatively rubber end caps 568 such as shown in FIG. 42 may be provided on the ends of such leg members.

Referring more particularly now to FIGS. 50 and 51, where central member 522 is shown in detail, an upwardly facing socket 524 for receiving a microphone stand rod or shaft 570 (see also FIGS. 53-54) to be held in a generally vertical orientation is secured. In the present embodiment, vertical support rod 570 is secured in socket 524 by a U-shaped clip and screw knob combination, whereby one of the legs of clip 572 is pressed inwardly against rod or shaft 570 by a screw knob 574. As best shown in FIG. 51, clip 572, which is preferably made from a semi-flexible metal material, is comprised of a pair parallel legs 576 and 577 joined together by another leg 578 extending perpendicularly between the ends of legs 576 and 577. Yet another leg 579 is connected to the opposite end of leg 576 and extends parallel to leg 578, but preferably does not connect to leg 577. A threaded aperture 580 is provided in leg 576, in which the threaded shaft of screw knob 574 is received. A threaded nut 581 may be welded to the front surface of opening 580 to provide a stronger threaded connection with knob 574, or other suitable alternative arrangements known in the prior art may be utilized. Meanwhile, a flattened section 582 is provided in socket 524, while an aperture 584 having a similarly flattened section 585 is provided in one of the side surface of central member 522. Clip 572 is sized so that when leg 577 is inserted extending downwardly into socket 524 in flattened section 582, leg 579 extends inwardly in flattened section 585 of aperture 584, while legs 576 and 578 fit snugly against the side and top of central member 522, respectively. Then, when microphone stand rod 570 is placed in socket 524, screw knob 574 is turned so that its end presses against the outwardly facing surface of leg 577 of clip 572, which leg in turn is pressed tightly into contact with stand rod 570, securing it in place in socket 524.

As shown in FIG. 54, stand base 510 is foldable into a compact storage arrangement, with all of the leg members of the stand being disposed vertically and closely spaced to each other. In addition, microphone stand rod 570 can also be more compactly stored along with stand base 510, with knob 574 being loosened so that lower end 586 of rod 570 can slide downwardly so that it is disposed between leg members 550 and 552, after which knob 574 is re-tightened to secure rod 570 in such position. This creates an even more compact storage arrangement for the combination of stand base 510 and rod 570, and in addition enables the entire stand to be more quickly deployed again into a use position, as all of the parts of the stand are already connected and aligned and are ready to be finally adjusted. However, if the microphone rod 570 is maintained upwardly or even removed and the length of the central member 522 is shortened, the packing of the leg member 550 and 552 can be made even more compact. Decreasing the length of the central member has the disadvantage of decreasing the maximum width of the entire microphone stand so it may not fit over certain wide amplifiers and the like equipment. Note that the microphone arrangement use on the microphone rod 570 may be other than the simple straight telescoping microphone support but may be a two-part cantilevered microphone stand extending backwardly particularly over or across a large amplifier between the extended legs of the microphone stand base.

In addition, a pair of threaded apertures are provided in the top surface of central member 522, in which screw knobs 590 and 592 are adjustably secured. See FIGS. 52 and 53. The benefit of such screw knobs 590 and 592 is that in addition to adjustable feet 566 being provided on the underside of legs 550 and 552 in some embodiments of the stand base, the knobs enable the angle of center leg pairs 530 and 542 as well as 532 and 544 on either side of center member 522 to be individually adjusted slightly as to the angle at which they are disposed. Turning screw knobs 590 and 592 so that the threaded screw bolt on the end of the knob enters further into the interior of devices 526 and 528, respectively, prevents center leg members 530 and 532 from being pivoted to a completely horizontal position. Although the stand base can be used effectively without such additional knobs, the advantage of such arrangement is that, as indicated by the double-ended arrows in FIG. 53, the amount of clearance underneath center legs 530 and 532 can be increased somewhat, particularly in the center, thereby allowing for extra room for passage of equipment wires and the like underneath such legs. As indicated above, a key advantage of the stand base of the present invention is that it allows other musical equipment to be placed directly in front of the user, just below or in front of the microphone stand rod 570. Not only is this more convenient for the user, but also it utilizes the space in a significantly more efficient manner, which is important in stage shows or on stages or other performing areas where there is little room left open for performers to maneuver. The more equipment that is placed around the stand base, the more likely it is that the wires will have different sizes or widths, and the present inventor has found that such extra clearance is desirable.

In accordance with the embodiments of the invention shown in FIGS. 39 through 54, not only is a superior more adjustable microphone or other performing stand provided, but a superior folding arrangement is provided in which the legs or base of the stand are enabled to fold close together and the microphone rod or support need not be removed and passed through the center of the folded base extending from the base at both ends as in the previously described embodiments. While the weaponlike appearance of such previous storage arrangement may be more desirable to some and less desirable to others, the present folding and storage arrangement can be set up and broken down much more quickly, as the main components of the stand base remain connected even as they are folded and stored. In accordance with the present embodiments, the base of the microphone in the letter "C" or "U" can be merely folded around one end or extending from one end of the microphone rod or slide to the center of the rod or completely separated from the rod in its own convenient to carry package.

While the present invention has been described at some length and with some particularity with respect to the several described embodiments, it is not intended that it should be limited to any such particulars or embodiments or any particular embodiment, but it is to be construed with references to the appended claims so as to provide the broadest possible interpretation of such claims in view of the prior art and, therefore, to effectively encompass the intended scope of the invention.

60 I claim:

1. A musical performer's stand base for supporting a generally vertically extending support member for at least one accessory to musical performance comprising:
  - (a) a central base portion for supporting the vertically extending support member;
  - (b) a pair of center leg members vertically pivotably connected at their inner ends to and with respect to the

25

- central base portion extending outwardly from opposite sides of the central base portion;
- (c) a pair of side leg members laterally pivotable from the ends of the pair of center leg members and extendable outwardly in the same plane as the longitudinal axis of the pair of center leg members;
- (d) the pair of center leg members being operatively pivotable to substantial alignment with the central base portion during use as a stand base and vertically pivotable into substantial parallel alignment with each other and substantial right angle relationship with the central base portion in storage and carrying position; and
- (e) the pair of side leg members being pivotable to substantially right angled relationship with the pair of center leg members during operative use as a stand base and pivotable to substantial parallel relationship with the center leg members in storage and carrying position.
2. A musical performer's stand base in accordance with claim 1 wherein the pair of center leg members are adjustable in length.
3. A musical performer's stand base in accordance with claim 2 wherein the pair of center leg members are telescopically adjustable in length.
4. A musical performer's stand base in accordance with claim 3 including slots in one or more of the outer members of the telescoping leg members providing a place for a fastener to pass in order to draw the inner and outer sections closer together for temporarily securing in place with respect to each other.
5. A musical performer's stand base in accordance with claim 2 wherein the pair of side leg members are extensible in length.
6. A musical performer's stand base in accordance with claim 5 wherein the pair of side leg members are telescopically extensible in length.
7. A musical performer's stand in accordance with claim 5 wherein the pairs of adjustable leg members are maintained in a desired extended or nonextended position by a friction grip arrangement.

26

8. A musical performer's stand base in accordance with claim 1 in which the pair of center leg members are vertically pivotable in an upward direction with respect to a support member for a musical accessory.
9. A musical performer's stand base in accordance with claim 1 in which the pair of center leg members are vertically pivotable in a downward direction with respect to a support member for a musical accessory.
10. A musical performer's stand base in accordance with claim 1 wherein the musical performer's stand in transportable mode is folded into a configuration in which the pairs of center and side leg members and any support member for a musical accessory are aligned substantially side by side in a row with each other for maximum compactness of structure for carrying and transportation.
11. A musical performer's stand base in accordance with claim 1 wherein the pair of center leg members are adapted to be biased in a slightly downward angle with respect to the central base portion in operation position such that the central base portion is somewhat raised to provide more room for wires and the like to pass under the central base portion with additional clearance.
12. A musical performer's stand base in accordance with claim 1 wherein detents are provided to hold the center leg members at desired angles with respect to the central base.
13. A musical performer's stand base in accordance with claim 12 wherein the detent is used to maintain the leg members in a folded position.
14. A musical performer's stand base in accordance with claim 1 wherein the central base portion is provided with an orifice in the top for mounting therein a microphone support rod.
15. A musical performer's stand base in accordance with claim 14 and including a flattened wedge arrangement which bears against the side of the support rod.
16. A musical performer's stand in accordance with claim 15 in which the flattened wedge is provided by the surface of a removable clip inserted into the support rod orifice and clamped to the side of the central base portion.

* * * * *
